UNITED STATES PATENT OFFICE.

LOUIS HUFFMAN, OF TORONTO, ONTARIO, CANADA.

IMPRESSION APPARATUS

938,381.

Specification of Letters Patent. Patented Oct. 26, 1909.

Application filed December 28, 1908. Serial No. 439,724.

To all whom it may concern:

Be it known that I, LOUIS HUFFMAN, of the city of Toronto, in the Province of Ontario, Canada, have invented certain new and useful Improvements in Impression Apparatus, of which the following is a specification.

This invention relates to apparatus in which rotary means are employed to produce a series of impressions at regular intervals on a continuous band of material drawn through the apparatus at a substantially uniform speed. Such impressions may, for example, be printed impressions as in a cylinder printing press, perforations as in a rotary perforator, or may amount to a complete severing of the material as in machines for dividing a band of material into sheets. In such apparatus, taking a cylinder printing press as a concrete example, it has heretofore only been possible, except in very imperfect manner and at a slow speed, to print impressions at intervals represented by the circumference of the cylinder, or aliquot parts thereof, and my object is to render it possible to make, at will and with a given cylinder or cylinders, impressions at intervals other than said intervals whether such impressions be in the nature of printing, or perforating, or dividing or any like operations.

In my previous application, No. 395,922, filed October 4th, 1907, I described and claimed means for accomplishing my object which comprised a cylinder formed in a plurality of independently concentrically journaled segments, forming less than the complete periphery of the cylinder, means for independently rotating each segment at an accelerated speed during part of each rotation, and means for varying the length of the arc in which acceleration takes place.

In my present invention I use two printing cylinders carrying segmental printing means each adapted for a differentiated motion during part of its revolution and set so that the second cylinder will print the blank spaces left by the first. The driving mechanism drives the printing cylinders at a uniform speed during the printing part of each revolution and may be set so that the printing part of a revolution be the same more or less, within the limits of adjustment of the device, and the remainder of the revolution are made in equal periods of time. A blank is thus left on the paper

by the first cylinder which may be filled in by the second cylinder. The paper is driven at a substantially constant and uniform speed and as the amount of paper required for two impressions varies with the length of the arc in which printing takes place means are provided for lengthening or shortening the path of the paper between the two printing cylinders.

Figure 1 is a side elevation of my improved machine. Fig. 2 is a plan view of the same. Fig. 3 is a longitudinal vertical section. Fig. 4 is an enlarged cross section taken through the driving shaft. Fig. 5 is an elevation on the same scale as Fig. 4 of the cam controlling the accelerating means. Fig. 6 is a side elevation of part of one of the clutches between the gearing and the driving shaft. Fig. 7 is an elevation of parts of the gearing showing particularly the rack operating the accelerating gear. Fig. 8 is a detail of part of the accelerating gear.

In the drawings like letters of reference indicate corresponding parts in the different figures.

A is the frame of the machine suitably shaped to support the different parts. In the frame are suitably journaled two printing cylinders B and C. Impression cylinders D and E are journaled respectively in suitable positions relative to the printing cylinders B and C.

F is the driving shaft. This shaft is provided with a gear wheel G driving by means of the gear train H the feed rollers I and by a gear train J the feed rollers K. The paper L passes between the feed rollers I between the two cylinders B and D and the two cylinders C and E, thence through the feed rollers K. As long as the shaft F is run at constant speed the feed of the paper will be uniform.

As set out in the preamble to the specifications it is my object to drive each of the printing cylinders B and C at a different speed during a portion of each rotation. This means that they cannot be driven from gearing secured to the driving shaft F. To secure this variable rotary motion of the printing cylinders I provide the gearing which I will now describe; and which periodically accelerates the speed of rotation of the cylinders. On the driving shaft are placed a pair of gear wheels M, M', and these gear wheels are given a driving connection with the shaft F by means of the

spring actuated free wheel clutches N, N', which enable the shaft to rotate the said gears but also allow the gears to run ahead of the shaft when necessary. Each of these 5 clutches comprises the part *a* fixed to the shaft and provided with rollers *b* movable in wedge-shaped recesses *c* formed by notching each fixed part at its periphery, so that the rollers are engaged by the inner peripheries 10 of the rings *d* formed on the gears M, M'. See Figs. 4 and 6. The bent springs *e* are suitably held in place and engage the rollers *b* and the parts *a* to press the said rollers toward the smaller ends of the recesses *c*. 15 These clutches are very effective and act promptly without permitting any slip or lost motion. Suitably pinned to or otherwise secured to the gear wheels M, M', are the disks 20 O, O'. These disks carry in suitable guides the slides P, P', each having a rack *f* formed thereon. The rack *f* on the slides P, P', engage gear pinions Q, Q'. See Fig. 7. Secured to the spindles *g* of the pinions Q, Q', are the pinions R, R'. The pinion R' meshes 25 with the gear S fast on the gear M, and the pinion R meshes with the gear S' fast on the gear M'. See Fig. 2. From this it follows that if, say, the slide P be operated, through the connected gearing the gear M' may be 30 caused to rotate at a higher speed than the shaft F, assuming that at the time the disk O carrying the slide P be rotating with the shaft. So also the slide P' may be operated 35 to cause the gear M to rotate faster than the shaft.

For the purpose of operating the slides P, P', I provide the following mechanism: T, T', are slides suitably carried in guides at each side of the apparatus. Each slide carries 40 a segmental cam ring *h*, which is secured to a disk *i* suitably supported so as to be rotatable in the slide T or T' by which it is supported. These disks *i* are centrally cut out for the passage of the shaft F. Each 45 disk *i* is provided with a slot *j* engaging a pin *k* fast on the frame of the apparatus. The slides T, T', are connected together by a cross bar *l*, which cross bar may be moved longitudinally on the machine by an adjusting screw *m* carried by the frame of the apparatus. By adjusting the screw the slides T, T', are moved longitudinally of the machine and at the same time the cam rings *h* are rotated in the slides. The slides P, P', 55 are provided with roller projections *n* passing through slots in the disks O, O', into positions to engage the cam rings *h*. I will take the operation of the parts at one side only of the apparatus for the purpose of 60 more definitely describing the operation.

Referring particularly to Fig. 5 I show different positions of the roller *n* of the adjacent slide P', as this projection is being carried around by the disk O'. It will be 65 noted the slide T' has been advanced so that

the cam ring *h* is eccentric to the shaft F consequently the projection as it rotates will come into engagement with the cam ring at about the point indicated in dotted lines at the right hand side of the drawing. As this movement continues it will be seen that the projection is gradually drawn in toward the shaft F until the projection escapes from the action of the cam ring at the point indicated in dotted lines at the left hand side of the drawing. This drawing in of the projection operates the slide P' which as already described drives the opposite gear M ahead of the shaft F. As soon as the projection *n* of the slide P' has escaped from the action 70 of the cam ring *h* with which it co-operates the projection *n* on the slide P at the opposite side of the machine has engaged the cam ring *h* carried by the slide T and the slide P is operated to cause a movement of 75 the gear M' ahead of the shaft. From this arrangement it follows that the movement of either gear wheel M, M', during its period of acceleration is made in exactly the same time as its movement while rotating 80 with the shaft, the relatively stationary controlling means for causing the acceleration at one side operating to accelerate the gear at the opposite side of the machine and to return the projection *n* at the opposite side 85 to a position ready to engage with the cam ring *h* at its own side of the apparatus.

It is evident that the arc through which the acceleration takes place is dependent on the extent of the inward movement of the 90 projections *n*, and this depends upon the eccentricity of the cam rings relative to the shaft F. The rotative movement of the cam ring *h* is necessary owing to the fact that each projection *n* must be maintained under 95 the control of its co-operating cam ring until the projection *n* at the opposite side is ready for engagement with its co-operating cam ring. If the cam rings are concentric with the shaft the cam rings must be rocked so 100 that each roller *n* is under control of its co-operating cam ring through an arc of 180 degrees, this arc being gradually decreased until the extreme adjustment of the machine 105 is reached, in the present case an arc of 135 110 degrees, during which acceleration takes 115 place.

From the arrangement described it is evident that the gear wheels M, M', will alternately rotate with the shaft and ahead of 120 the shaft, the acceleration of one gear wheel taking place while the other is moving with the shaft.

The features of the gearing which are most important and which need to be clearly 125 understood are the arrangement whereby the printing part of each revolution of each printing cylinder is made in the same period of time as the non-printing part of the revolution and the arrangement whereby the 130

operation of one of the accelerating means returns the opposite accelerating means to a condition ready for action in its turn.

It will be readily seen, it is thought, that the drawing inward of one of the projections n , while the disk on which it slides is rotating with the shaft, will advance the gear wheel M or M' at the opposite side of the gearing. The second projection n at the advancing side is then in its position closest to the axis and the actuation of the slide which carries it by the pinion Q or Q' will move the said projection out ready for action in its turn. The outward movement of this second projection n on the advancing disk has no retarding effect on the gear wheel and disk at the first mentioned side since the disk on which it is carried is running ahead of the shaft to just the same extent as its outward movement would tend to retard the gear-wheel and disk at the said first mentioned side of the gearing, and the two movements being equal and opposite neutralize one another.

It is evident that the arc of acceleration must depend on the extent of the inward movement of the projections n ; and the time in which the acceleration takes place must depend on the speed at which this inward movement takes place. To insure therefore that the accelerating and non-accelerating parts of each rotation takes place in the same time the cam rings h must be set so that the desired inward throw is given—which is obtained by the eccentricity of the cam rings—and so that each projection n is controlled by its cam ring only through an arc equivalent to the arc in which acceleration is to take place—which is secured by having a suitable proportion of the cam ring in position for engagement by the projection. Consequently to vary the arc of acceleration while having the acceleration take place in the same time as the non-accelerating part of a rotation of a printing cylinder, two adjustments are necessary; the eccentricity of the cam rings must be variable to vary the inward throw of the projections n and at the same time the cam rings must rotate to vary the arcs of engagement with said projections. How this is done has already been clearly described. It is clear then that for any arc of acceleration the time of acceleration is set by the adjustment of the cam rings so that the accelerating and non-accelerating arcs (*i. e.* the printing and non-printing parts of each rotation of each printing cylinder) are passed through in equal times, which is essential to the proper operation of the device.

The gear wheels M , M' , are meshed with gear pinions U , U' , fast on independent shafts V , V' , carrying the gears o and p . The gear o by a suitable train of gearing g drives the impression cylinder D and print-

ing cylinder B , while the gear p by a suitable train of gearing r drives the impression cylinder E and the printing cylinder C . The printing and impression cylinders will thus partake of the movements of the gears M , M' , so as to alternately run at a uniform speed during part of each revolution and at an accelerated speed during the remainder of each revolution. The printing cylinders will be provided with segmental stereotypes or other printing means so placed that the printing impression of each printing cylinder will take place during such time as it is moving at its uniform speed which will from the mechanism described necessarily be at the same rate of speed as the travel of the paper. The impressions of the cylinders as the machine is arranged will also take place alternately, one printing while the other is missing. The printing cylinders are also properly spaced so that their impressions will alternate on the paper fed through the machine. It follows that as the arc through which the printing movement of each printing cylinder takes place may be varied, and as the accelerated motion takes place in the same space of time as the normal motion of rotation it follows that when the accelerating arc is large and the printing arc small smaller printing plates may be employed, and that the impressions of each printing cylinder will be shorter in length and follow at shorter intervals. Consequently, in order that the second printing cylinder may accurately fill in the gaps left by the other printing cylinder it is necessary that there shall be more or less paper between the two printing cylinders according to the adjustment of the machine. I make this adjustment by causing the paper to follow a longer or shorter path as may be necessary. For this purpose I provide a stationary guide roller s journaled on the frame of the machine and a movable guide roller t . This movable guide roller is journaled in slides u suitably guided at opposite sides of the machine. Each slide is formed as a rack and these racks are engaged by pinions v fast on a spindle w journaled on the frame of the machine and provided with a crank handle a' . The clamping screws b' are preferably provided for holding the slides u as adjusted.

The mechanism described I find effectively accomplishes the object of my invention. The printing cylinders rotate at a uniform speed during the printing part of each rotation, and consequently they coöperate satisfactorily with the paper, which can only successfully be fed at a uniform rate of speed. With my mechanism also the speed of the printing cylinders during the printing remains the same no matter what the adjustment of the machine may be within its limits, so that there is no necessity to pro-

vide any means for varying the rate of feed of the paper and the output of the machine in any superficial area of printed surface will remain substantially the same at all adjustments. This is something not heretofore 5 accomplished as far as I am aware. The impression cylinders also being geared to the printing cylinders revolve synchronously therewith, and thus the same part of an impression cylinder will always coöperate with 10 a given part of one of the printing segments. This is important in printing as it is usually necessary to pad certain portions of the impression rollers to produce uniform imprints. It will be understood that instead of stereotypes or electrotypes that perforating, dividing or other impression devices may be 15 employed.

What I claim as my invention is:—

1. In a rotary printing press rotary printing means forming a segment of a cylinder in combination with means for driving said printing means at a uniform speed during the printing part of each rotation and at a different speed during the non-printing part of each rotation; and means for varying the length of the arc in which printing takes place without varying the speed during printing which remains relatively constant for all settings of the device. 20

2. In a rotary printing press rotary printing means forming a segment of a cylinder in combination with means for driving said printing means at a uniform speed during the printing part of each rotation and at a different speed during the non-printing part of each rotation; and means for varying the length of the arc in which printing takes place without varying the speed during printing, which remains relatively constant for all settings of the device, the driving and adjusting means being arranged to cause the non-printing part of each rotation at any given setting to take place in the same 35 length of time as the printing part of the rotation. 40

3. In a rotary printing press the combination of segmental rotary printing means; paper feeding means; a shaft; gearing between the paper feeding means and the shaft; gearing between the printing means and the shaft rotating the printing means at the same speed as the shaft during the printing part of each rotation; and means 50 for driving the printing means at a different speed during the non-printing part of each rotation. 55

4. In a rotary printing press the combination of segmental rotary printing means; 60 paper feeding means; a shaft; gearing between the paper feeding means and the shaft; gearing between the printing means and the shaft rotating the printing means at the same speed as the shaft during the 65 printing part of each rotation; means for

driving the printing means at a different speed during the non-printing part of each rotation; and means for varying the length of the arc in which printing takes place. 70

5. In a rotary printing press the combination of segmental rotary printing means; paper feeding means; a shaft; gearing between the paper feeding means and the shaft; gearing between the printing means and the shaft rotating the printing means 75 at the same speed as the shaft during the printing part of each rotation; means for driving the printing means at a different speed during the non-printing part of each rotation; and an impression cylinder geared 80 with the printing cylinder to rotate in synchronism therewith.

6. In a rotary printing press the combination of rotary printing means forming a segment of a cylinder; paper feeding means 85 operating at a uniform speed; means for driving the printing means at the same speed as the paper during the printing part of each rotation and at a different speed during the non-printing part of each rotation; and means for varying the arc in which printing takes place without varying the speed. 90

7. In a rotary printing press the combination of rotary printing means forming a 95 segment of a cylinder; paper feeding means operating at a uniform speed; means for driving the printing means at the same speed as the paper during the printing part of each rotation and at a different speed 100 during the non-printing part of each rotation; and means for varying the arc in which the printing takes place without varying the speed, the driving and adjustable means being adapted to cause the non-printing part of each rotation to take place in the same length of time as the printing part of the rotation. 105

8. In a rotary printing press a plurality of independent segmental rotary printing 110 means, in combination with means for driving each of said printing means arranged to rotate the printing means during the non-printing part of each rotation, at a different speed from the speed during the printing 115 part of each rotation, the driving means being also arranged to cause impressions of the printing means to alternate. 120

9. In a rotary printing press a plurality of independent segmental rotary printing 120 means, in combination with means for driving each of said printing means arranged to rotate the printing means during the non-printing part of each rotation at a different speed from the speed during the printing 125 part of each rotation, the driving means being also arranged to cause impressions of the printing means to alternate and to cause the non-printing part of each rotation of each printing means to take place in the 130

same length of time as the printing part of the rotation.

10. In a rotary printing press a plurality of independent segmental rotary printing means, in combination with means for driving each of said printing means at a uniform speed during the printing part of each rotation and at a different speed during the non-printing part of each rotation, the driving means being arranged to cause the impressions of the printing means to alternate.

11. In a rotary printing press a plurality of independent segmental rotary printing means, in combination with means for driving each of said printing means arranged to rotate the printing means during the non-printing part of each rotation at a different speed from the speed during the printing part of each rotation, the driving means being also arranged to cause the impressions of the printing means to alternate; and means for varying the length of the arc in each printing means in which printing takes place.

25. 12. In a rotary printing press a plurality of segmental rotary printing means, in combination with means for driving each of said printing means at a uniform speed during the printing part of each rotation and at 30 a different speed during the non-printing part of each rotation, the driving means being arranged to cause the impressions of the printing means to alternate; and means for varying the length of the arc in each printing means in which printing takes place.

13. In a rotary printing press a plurality of independent segmental rotary printing means, in combination with means for driving each of said printing means at a uniform speed during the printing part of each rotation and at a different speed during the non-printing part of each rotation, the driving means being arranged to cause the impressions of the printing means to alternate; and means for varying the length of the arc in each printing means in which printing takes place without varying the speed during printing which remains relatively constant for all settings of the device.

50. 14. In a rotary printing press a plurality of independent segmental rotary printing means, in combination with means for driving each of said printing means at a uniform speed during the printing part of each rotation and at a different speed during the non-printing part of each rotation, the driving means being arranged to cause the impressions of the printing means to alternate; and means for varying the length of the arc in each printing means in which printing takes place without varying the speed during printing which remains relatively constant for all settings of the device, the driving and adjusting means being arranged to 65 cause the non-printing parts of each rotation

of each printing means at any given setting to take place in the same length of time as the printing part of the rotation.

15. In a rotary printing press a plurality of independent segmental rotary printing means, in combination with means for driving each of said printing means, arranged to rotate the printing means, during the non-printing part of each rotation, at a different speed from the speed during the printing part of each rotation, the driving means being arranged to cause the impressions of the printing means to alternate; means for varying the length of the arc in each printing means in which printing takes place; paper feeding means; and means for varying the length of the path of the paper between the two printing means.

16. In a rotary printing press a plurality of independent segmental rotary printing means, in combination with means for driving each of said printing means at a uniform speed during the printing part of each rotation and at a different speed during the non-printing part of each rotation the driving means being arranged to cause the impressions of the printing means to alternate; means for varying the length of the arc in each printing means in which acceleration takes place; paper feeding means; and means for varying the length of the path of the paper between the printing means.

17. In a rotary printing press provided with rotatable printing means, means for imparting a variable rotary motion to the printing means comprising a shaft; gearing between said shaft and the printing means; a free wheel clutch driving connection between the shaft and the gearing; and means for accelerating the gearing during part of each rotation to run ahead of the shaft.

18. In a rotary printing press provided with rotatable printing means, means for imparting a variable rotary motion to the printing means comprising a shaft; gearing between said shaft and the printing means; a free wheel clutch driving connection between the shaft and the gearing; and means rotating with the gearing for accelerating the gearing during part of each rotation to run ahead of the shaft; and relatively stationary means controlling the movements of the accelerating means.

19. In a rotary printing press provided with rotatable printing means, means for imparting a variable rotary motion to the printing means comprising a shaft; gearing between said shaft and the printing means, a free wheel clutch driving connection between the shaft and the gearing; means rotating with the gearing for accelerating the gearing during part of each rotation to run ahead of the shaft; and adjustable relatively stationary means controlling the movements of the accelerating means.

20. In a rotary printing press the combination of paper feeding means; rotatable printing means; a shaft geared to the paper feeding means; gearing between the shaft and the printing means; a free wheel clutch driving connection between the shaft and the gearing; means rotating with the gearing for accelerating the gearing during part of each rotation to run ahead of the shaft; relatively stationary means for controlling the movements of the accelerating means.
- 10 21. In a rotary printing press the combination of paper feeding means; rotatable printing means; gearing between the shaft and the printing means; a free wheel clutch

driving connection between the shaft and the gearing; means rotating with the gearing for accelerating the gearing during part of each rotation to run ahead of the shaft; relatively stationary means for controlling the movements of the accelerating means; and means for adjusting the controlling means to vary the arc through which acceleration takes place.

Toronto this 21 December, 1908.
